SHEET ALIGNING CLAMPHarold E. Erwin, 2117 Missouri St., Keokuk, Iowa
Filed Feb. 14, 1963, Ser. No. 258,475
1 Claim. (Cl. 113—99)

This invention relates to an implement of extremely simple construction capable of being readily clamped to adjacently disposed edge portions of two plate members for holding said plate members in alignment and immovable relative to one another while the plate members are secured together by as by tack welding.

More particularly, it is an object of the present invention to provide an implement for the afore-described purpose which will effectively move two plates into correct alignment with one another and thereafter maintain the plates in proper aligned relationship while being permanently attached to one another, to thereby eliminate the need for welding elements to the plates and which elements can be engaged by tools or implements used to position and hold the plates, while the plates are being secured together, and which elements must thereafter be removed from the plates.

Still another object of the invention is to provide an implement which will effect a material saving in time and labor involved in fabricating tanks and other containers and structures from large preshaped rigid metal sheets or plates.

Still another object of the invention is to provide an implement which may be readily released without being disconnected from the plates to which it is attached for moving the implement to different positions along the adjacent edges of the plates being secured together, as the operation of securing the adjacent plate edges together progresses, to thereby facilitate the fabrication of a tank or other structure.

Still a further object of the invention is to provide a plate clamping implement which may be utilized for correctly aligning plates of different thicknesses and with desired complementary sides of the plates disposed flush with one another.

Various other objects and advantages of the invention will hereinafter become more fully apparent from the following description of the drawings, illustrating a presently preferred embodiment thereof, and wherein:

FIGURE 1 is a perspective view showing the plate fabricator in an applied position clamped to plates which are disposed one above the other for holding the plates correctly aligned with one another while their adjacent horizontal edges are secured together;

FIGURE 2 is an enlarged longitudinal sectional view taken substantially along the line 2—2 of FIGURE 1;

FIGURE 3 is a cross sectional view through the implement taken substantially along a plane as indicated by the line 3—3 of FIGURE 2, and on an enlarged scale;

FIGURE 4 is a longitudinal sectional view taken substantially along the line 4—4 of FIGURE 2 and with one of the parts omitted;

FIGURE 5 is a fragmentary top plan view, partly in section, and showing one end portion of the implement;

FIGURE 6 is an end elevational view of the implement looking from right to left of FIGURES 2 and 5, and

FIGURE 7 is a perspective view, similar to FIGURE 1, and showing the implement applied to two horizontally spaced plates and engaging adjacent vertically spaced edges thereof.

Referring more specifically to the drawings, the metal plate fabricator or clamping and aligning implement in its entirety and comprising the invention is designated

2

generally 10 and includes a section, designated generally 11, and a section designated generally 12.

The section 11 includes an elongated abutment member 13 of hollow rectangular construction in cross section having flat opposite sides 14 and 15 which are provided with corresponding transversely extending aligned openings or slots 16 and 17, respectively.

A lower block 18 and an upper block 19 are secured, as by welding, as seen at 20, to the outer surface of the side 15. Said blocks 18 and 19 are elongated and of rectangular shape and extend longitudinally from the abutment member 13. The upper surface 21 of the bottom block 18 is disposed substantially flush with the bottom surface of the slot 17, and the bottom surface 22 of the upper block 19 is disposed substantially flush with the upper edge of the slot or opening 17, as best seen in FIGURE 2. The upper block 19 has a threaded bore 23 which extends from top to bottom therethrough and which is located near the outer end of said block. The upper surface 21 of the lower block 18 has a concave countersink or depression 24 therein which aligns with the bore 23. A setscrew 25 is threaded downwardly through the bore 23. Setscrew 25 and the blocks 18 and 19 combine to form an anchoring unit of the section 11.

The section 11 also includes a block or square nut 26 which is secured, preferably by welding, as seen at 27, on the upper end of the abutment member 13 and which has a threaded bore 28 which extends therethrough in a direction perpendicular to the sides 14 and 15. A screw 29 extends threadedly through the bore 28 and has a rounded or hemispherical end 30 disposed over the side 14 and normally setback relative to the outer surface of said side.

The section 12 includes an elongated rigid hollow or tubular body 31 having an end wall 32 at one end thereof which is provided with a central opening 33. The other end of the tubular member 31 is open and is defined by an annular edge 34 which is disposed in a plane normal to the axis of the member 31. The member 31 is provided with an elongated longitudinally extending slot 35 which extends from near the end 34 thereof to beyond a midpoint of said member 31. The member 31 constitutes the abutment member of the section 12.

The section 12 includes a pulling unit, designated generally 36, which includes an elongated bolt or threaded rod 37, constituting a stem, which extends slidably through the end wall opening 33. The bolt 37 has a head 38 at one end thereof which is reciprocably disposed in the hollow abutment member 31 and which is elongated in a direction lengthwise of said bolt or rod. The head 38 has a recess 39 which opens outwardly of the end thereof which is disposed remote from the bolt 37 and which is of a length preferably somewhat greater than one-half the length of the head 38 and of a width nearly equal to the width of the portion of said head in which the recess is formed, as best seen in FIGURE 3, so that said recess is open only at its outer end. The head 38 has a transversely disposed threaded bore 40 which opens outwardly of a portion of the periphery thereof and into the recess 39 through one side of said recess. The threaded bore 40 is disposed perpendicular to the recess 39 and has a setscrew 41 threadedly engaging therein and which projects outwardly through a portion of the slot 35, in which said screw 41 slidably fits. The surface 42 of the recess 39, located opposite to the surface thereof through which the bore 40 opens into the recess 39, has a countersink or concave depression 43 which aligns with the bore 40. The screws 25 and 41 have rounded or hemispherical leading ends 44 and 45, respectively.

A nut 46, constituting a part of the pulling unit 36, threadedly engages the bolt or rod 37, beyond the end wall 32, and elongated rigid members 47, forming handles, are welded or otherwise rigidly secured as seen at 48 to opposite sides of the nut 46 and extend in opposite directions from said nut. A washer 49 is loosely disposed on the bolt 37 between the end wall 32 and nut 46.

The fabricating implement 10 also includes a non-elastic metal strap element 50 for connecting the sections 11 and 12 to one another and which is of a width and thickness less than the width and thickness respectively of the slots 16 and 17 and the recess 39. A part of the connecting element 50 extends through the slots 16 and 17 and longitudinally between the faces 21 and 22 of the blocks 18 and 19 and is anchored to the section 11 by tightening the setscrew 25. The setscrew 25 is shown tightened in FIGURE 2 so that its ballpoint 44 has deformed a portion of the connecting element 50 into the depression 24, as seen at 51, to securely anchor the connecting member to said section 11. The connecting element 50 extends through the open end 34 of the abutment member 31 and has its other end disposed in the recess 39. Said end is anchored to the pulling unit 36 by tightening the setscrew 41 so that its rounded leading end deforms a portion 52 of the connecting member 50 into the countersink 43 to thus securely anchor the connecting element to the pulling unit of the section 12. The width of the recess 39 corresponds to the width of the slots 16 and 17 and when the sections 11 and 12 are connected together by the element 50 said recess 39 aligns with the slots 16 and 17.

FIGURE 1 illustrates the fabricating implement 10 being used for holding a plate 53 correctly aligned relative to a plate 54, which is disposed therebeneath. The plates 53 and 54 are of rigid preshaped metal construction and as shown constitute parts of a tank being fabricated. The lower plate 54 has been previously assembled and secured on a base or other plate disposed therebeneath, not shown. Any suitable lifting device, not shown, may be utilized for supporting the upper plate 53 in approximately its position of FIGURE 1. Spacer elements 55 and 56 of a thickness greater than the thickness of the connecting element 50 are disposed between the adjacent edges 57 and 58 of the plates 53 and 54, respectively. In connecting the sections 11 and 12 so as to be disposed on opposite sides of the plates 53 and 54, the connecting element 50 can be anchored to the section 11 by the setscrew 25 and inserted between the edges 57 and 58 and into the recess 39 and anchored to the head 38 by tightening the setscrew 41. In accomplishing this connection to the head 38, the nut 46 can be backed off sufficiently so that the head 38 can be located with the open end of its recess 39 in close proximity to the open end 34 of the body 31. The fabricating implement 10 would initially be disposed at the right of its position of FIGURE 1 near and to the left of the tack welds 60 and with the spacer 55 located between said tack welds. After the two tack welds 59 and 60 have been formed, the actuator 46, 47 is manually turned counterclockwise to release the pulling force on the element 50 and so that the implement 10 can be slid from right to left of FIGURE 1 to its position as shown in this view. The actuator 46, 47 is then turned clockwise to exert a pulling force outwardly on the pulling unit 36 for drawing the connecting element 50 inwardly of the member 31 so that the side 14 will abut flush against the outer or right hand sides of the plates 53 and 54, as seen in FIGURE 2, and the edge 34 will abut flush against the other left hand sides of said plates, to hold the plates in alignment with one another and to clamp said plates immovable to one another while another tack weld is formed immediately to the right of the implement 10, as seen in FIGURE 1. The slight curvature of the preshaped plates 53 and 54 is not sufficient to prevent the implement from holding the plates in correct alignment while the spaced

tack welds are formed. It will be understood that after each tack weld the implement 10 is loosened and advanced a predetermined distance away from the last formed tack weld, and that the spacing elements 55 and 56 are also periodically moved along with the implement 10, and with the spacer 55 being maintained between the last formed tack weld and the next weld to be formed.

FIGURE 7 shows the implement 10 utilized for holding two circumferentially spaced plates 61 and 62 correctly aligned with one another and while tack welds 65 are formed to secure the adjacent vertical edges 63 and 64 of said plates together. In this operation the implement 10 is advanced upwardly and with the spacers 55 and 56 utilized in the same manner as aforescribed. Where the plates 61 and 62 are previously welded to plates or other elements disposed therebelow and not shown, no separate supporting device for the plates 61 and 62 is required.

It will also be apparent that a plurality of the implements 10 may be utilized at spaced intervals between adjacent edges of plates or sheets to be welded, by utilizing additional spacing elements 55 and 56, so that a number of tack welds can be made before moving the implements 10. When a plurality of the implements 10 are thus utilized an implement 10, when necessary, can be completely disconnected from the plates being assembled by loosening the setscrew 41 to detach the connecting element 50 from the section 12.

In some fabricating operations an upper plate of a lesser thickness than a plate disposed immediately therebeneath is employed. In such a situation the edge 34 is positioned against the sides of the plates which are to be disposed flush with one another and the setscrew 29 is advanced from right to left of FIGURE 2 so that its ballpoint 30 will protrude from the plane of the outer surface of the side 14 a distance corresponding to the difference in thickness of the two plates and so that the screw 29 can then hold the upper plate tight against the abutment member 31.

It will be understood that after the plates or sheet members have been secured together utilizing one or more of the fabricating implements 10, that the adjacent edges thereof are thereafter completely welded.

Various modifications and changes are contemplated and may be resorted to, without departing from the function or scope of the invention as hereinafter defined by the appended claim.

I claim as my invention:

An implement for holding metal plate elements correctly aligned for fabricating comprising an elongated nonelastic connecting element adapted to extend freely through a gap between adjacent edges of two plates for connecting first and second implement sections disposed on opposite sides of said plates, said first implement section including an abutment member having a side adapted to abut corresponding sides of the plate and extending across said edges, said abutment member having a slot aligning with the gap between said edges and through which a part of the connecting element extends, anchoring means secured to and projecting from an opposite side of said abutment member and in which the connecting element is anchored at any desired distance from an end of the connecting element, said second section including an abutment member having a portion engaging flush against the other sides of the plates and defining an opening through which said end of the connecting element extends, a manually actuated pulling unit supported by said abutment member of the second section including means for detachably securing said end of the connecting element thereto, said pulling unit including a manually actuated part for exerting a pulling force on said end of the connecting element in a direction axially of the connecting element for drawing said abutment members toward one another for clamping the plates immovably therebetween and in alignment with one another.

other, and means carried by said first mentioned abutment member and manually adjustable for displacing one of said plates away from the first mentioned abutment member and toward said second mentioned abutment member for positioning the sides of the plates engaged by the second mentioned abutment member in alignment with one another.
